P. L. WEST, OF BATH, ILLINOIS.

Letters Patent No. 63,447, dated April 2, 1867; antedated March 19, 1867.

IMPROVEMENT IN CULTIVATORS.

The Schedule referred to in these Letters Patent and making part of the same.

TO ALL WHOM IT MAY CONCERN:

Be it known that I, P. L. WEST of Bath, in the county of Mason, and State of Illinois, have invented certain new and useful Improvements in Cultivators; and I do hereby declare that the following is a full and clear description thereof, reference being had to the accompanying drawings, and to the letters of reference marked thereon.

Figure 1 of the drawings is a plan of the improved cultivator.

Figure 2 is a vertical sectional elevation of it, taken on the line *x y* in fig. 1.

This invention relates, firstly, to the manner of connecting the ploughs to the frame; secondly, to the arrangement for giving the ploughs lateral motion; and thirdly, to the devices for lifting the ploughs up out of the ground.

To enable those skilled in the art to make and use my improved cultivator, I will proceed to describe its construction and operation.

A is the framework on which all other parts of the machine are built. On each side of this frame there is a metallic arm, on which is placed a wheel, B, for supporting and transporting the machine. These metallic arms should be of cast metal, and in such a form that they may be readily bolted to the frame A by means of flanges on their back ends, or slots cut therein. The swinging bar C is placed inside of the frame A, near its forward end, and connected with it by means of the two links *a*. On top of each of the side beams of the frame A there is a lever, C¹, pivoted to it at *c*, so that the ends of the said levers will have a lateral motion. The forward ends of these levers are connected with the links *a* by means of the connecting-rods C². The back ends of the levers C¹ are connected by means of the straps *c'* with the treadle bars C³, the forward ends of which bars are hinged to the bottom sides of the side beams of the frame A in such a manner that they may receive a slight vertical motion. The straps *c'*, in passing from the levers C¹ to the treadle bars C³, are conducted outside of the frame A, when they pass over pulleys at the point where the horizontal direction of them is changed to a vertical direction. As the driver of this machine is seated on the seat S he will place his feet on the back ends of the treadles C³, which project inside of the frame A sufficiently to allow foot room for this purpose. The driver can, by pressing down either foot at pleasure, cause the back end of the lever C¹, which is connected with the treadle pressed down, to move laterally outward toward the wheel B on that side of the frame. This motion of the said lever will be transmitted to the swinging bar C through the medium of the connecting-links *a* and connecting-rods C². As both of the forward ends of the levers C¹ are connected with the swinging bar C, the motions of the two levers, as aforesaid, will be in harmony with each other, and the two treadles C³ will both move at the same time, but in opposite directions, that is, when one treadle is moved downward the other one will move upward at the same time. The two ploughs D are intended to travel inside of the frame A, and the forward ends of their beams are connected by means of the curved metal draught-rods *d* with the swinging bar C. The two posts *d'* of these ploughs are connected together by means of the links *d''*, so that the two ploughs will uniformly remain the same distance apart. As the driver sits upon his seat he can easily grasp with his hands the handles *d³* of these ploughs, which are thereby rendered wholly under his control. In order to guide the ploughs D in a lateral or diagonal direction, so as to accommodate the sinuosities of the rows of plants being cultivated, all the driver will have to do will be to press with one or the other of his feet upon the treadle on the opposite side of the machine to which he wishes to cause the ploughs to run. This action will swing the bar C to one side, as has already been described, and the plough beams will accordingly be led in the same direction. When the driver wishes to raise the ploughs D up out of the ground he will do so by raising them up by means of the handles *d³*, high enough to let the props *d⁴* drop on top of the cross-beam A' of the supporting frame. When the ploughs are let down all that will be necessary will be to seize the props *d⁴* and draw them back from their bearing on the beam A'. In case it is desirable to turn up a greater breadth of soil than can be done by the ploughs D, I attach two more ploughs, D¹, to the posts D², the said posts being pivoted to the frame A at the point *a'* a little in the rear of the driver's seat. These ploughs and their posts are to be raised up out of the ground by means of cords *d⁵*, passing from the said posts near their lower ends up to and over the pulleys *d⁶*, and thence down to the treadle *d⁷*, which are in a suitable position for the driver to place his feet upon, which he will do, and press down thereon with his weight when he wishes

to raise the said ploughs. The segmental bars D^3 , attached to the frame A near or at their upper ends, extend thence down through a mortise in the posts D^2 , and a pin or lug, d^8 , placed at a proper point in the said curved bars behind the posts D^2 , will prevent the said posts and their ploughs from going further back than they should, and hold them to their work. The ploughs D^1 may be shovel-ploughs.

Having described my invention, what I claim is—

1. The construction and arrangement herein shown and described of the ploughs D^1 , and their attachment links d^2 , and their draught-rod d .
2. I claim the device C, a , C' , C^1 , C^2 , and c' , for giving the ploughs D^1 the requisite lateral motion.
3. I claim the combination and construction of the posts d^1 and the props d^4 , substantially as described and set forth.
4. I claim the construction and arrangement of the ploughs D^1 and curved bars D^3 ; also the device d^5 , d^6 , and d^7 for raising the said ploughs up out of the ground, substantially as described and set forth.

P. L. WEST.
